UNITED STATES PATENT OFFICE

155,612

DESIGN FOR A COMBINED DOOR GUARD AND PLAQUE

Lewis L. Kadleck, Dallas, Tex.

Application May 14, 1946, Serial No. 129,705

Term of patent 14 years

(Cl. D13—1)

To all whom it may concern:

Be it known that I, Lewis L. Kadleck, a citizen of the United States of America, residing at Dallas, county of Dallas, and State of Texas, have invented a new, original, and ornamental Design for a Combined Door Guard and Plaque, of which the following is a specification, reference being had to the accompanying drawing, forming a part thereof, wherein:

Figure 1 is a face view of a combined door guard and plaque, showing my new design;

Figure 2 is an edge view;

Figure 3 is a top edge view;

I claim:

The ornamental design for a combined door guard and plaque, as shown.

LEWIS L. KADLECK.
